EDWARD L. ACKERMAN AND ALOIS J. ZWIERZINA, OF DETROIT, MICHIGAN, ASSIGNEES TO ACKERMAN-BLAESSER-FEZZEY, INC., OF DETROIT, MICHIGAN, A CORPORATION OF MICHIGAN.

SASH-OPERATING MECHANISM.

Application filed March 5, 1925. Serial No. 13,392.

This invention relates to sash operating mechanism particularly adapted for use in operation of sliding sash of closed automobile bodies, and the object of the invention is to provide a simple and inexpensive device including a lazy tong structure expanded and constructed by means of a rack and gear for raising or lowering the sash.

A feature of the invention is involved in the rack and gear device and in the operating means for the gearing by which the sash is automatically locked in position at any point of its travel.

A further feature of the invention resides in the utilization of a lazy tong structure and the means for operating the same whereby comparatively short movement of a rack through operation of a gear causes the sash to move a much greater distance whereby by a few turns of the gear the sash may be fully raised or lowered.

These and other objects and novel features of the invention are hereinafter more fully described and claimed, and the preferred form of construction of sash operating mechanism embodying our invention is shown in the accompanying drawings in which—

Fig. 1 is an elevation showing our improved operating mechanism in conjunction with a sash and frame in which the sash is slidable.

Fig. 2 is a section taken on line 2—2 of Fig. 1.

Fig. 3 is an enlarged section showing the lock device.

Fig. 4 is an elevation partly in section taken on line 4—4 of Fig. 3.

Fig. 5 is a section of the lock device taken on line 5—5 of Fig. 4.

Fig. 6 is a detail in perspective of part of the lock structure.

In Fig. 1 a part of a frame 1 is shown. This is provided with grooves in the vertical side members to receive opposite side edges of the sash or glass 2 and in Fig. 1 it is to be understood that the glass is forward of the cross bar 3 extending between the vertical side members of the frame or recess in which the sash is movable. The operating mechanism is mounted on this bar 2 between the face of the bar and the glass and consists of a gear 4 on the shaft 5 on which shaft is a gear 6 meshing with a ver-

tically movable rack 7 in a case 8 which encloses the rack and the gear 6 and is securely attached by bolts 9 to the cross bar 3. In the casing 10 mounted on the cross bar is a gear 11 meshing with the gear 4 and, by rotation of this gear 11 by means of a handle 12 as hereinafter described, the gear 6 is turned and moves the rack 7 up or down in its case 8.

Extending from the cross bar 3 to the bottom of the recess is a plate 13 having a vertical slot 14 therein and pivotally secured to the lower end of the plate 13 are the bars 15 and 16 of the lazy tongs, the outer ends of which are pivoted to the bars 17 and 18 which in turn are pivoted together on the pin 19 and the upper ends of which are outwardly and downwardly curved and provided with rollers 20 which ride in a way 21 provided at the bottom edge of the sash. At the point of connection of the members 17 and 18 with the bars 16 and 15 respectively is positioned a coiled spring 22, the inner end of which is attached to the pivot pin 23, the outer end of which is connected with a pin 24 in each arm 17 and 18 for the respective springs. These act as counterbalances for the weight of the sash.

The lower end of the rack 7 has a lug 25 which rides in the slot 14 providing a guide therefor and this lower end is connected with the lazy tongs structure by the two links 26 and 27 together pivoted at their upper ends to the lower end of the rack by means of a pivot pin 28 and each respectively pivoted at the lower end at 29 and 30 practically centrally of the bars 16 and 15. By this arrangement it will be understood that rotation of the gear 4 and consequent rotation of the gear 6 raises or lowers the rack 7 in the case 8 provided therefor and this movement downward for instance pushes on the bars 16 and 15 tending to collapse the lazy tongs and to move the sash downward in the recess provided therefor, and upward movement of the rack pulls on these bars 15 and 16 elongating the lazy tongs and raising the sash. By this specific connection of the links midway of the length of the arms 15 and 16 very little longitudinal movement of the rack 7 causes a considerable movement of the lazy tongs and thus enables the sash to be completely raised or lowered by very little rotation of the handle mem-

ber, practically three turns of the gear being sufficient for complete operation of the sash in either direction.

It is very desirable that, in the movement 5 of the sash to any position partly closed for ventilation of a vehicle body, the sash be locked so that road shock occurring in operation of the vehicle will not cause the sash to drop and increase the opening. To accomplish this purpose we have provided a 10 peculiar construction of operating member illustrated more clearly in Figs. 2 to 6 from which it will be observed for instance in Fig. 5 that the operating handle 12 is secured to 15 a stud 31 which extends thru the cross bar 3 and is there provided with an enlarged cylindrical part 32 on which is rotatably mounted the gear 11. This stud extends into the block 33 fixedly secured in any appropriate 20 manner to the enclosing case 10 which is slotted on one side indicated at 34 to receive the gear 4 which meshes with the gear 1. On this stub shaft 31 lying between the gear and the cylindrical stationary boss 33 25 is an actuator 35 which has an elongated slot 36 therein shown in Fig. 6 which fits a similarly shaped piece 37 on the stud shaft and is thus rotatable with this stud shaft. This member 35 has two upstanding lugs or 30 ears 38 and 39 shown clearly in Figs. 3 and 6 which are spaced apart as shown and between which lugs is positioned a pin 40 fixed in the gear as shown in Fig. 5. On the stationary boss 33 is a coiled spring 41 35 which is made in a coil slightly less in diameter than the diameter of the member 33 and thus tightly fits the same. The ends of this coiled spring 42 and 43 cross as shown in Fig. 4 to opposite sides of the pin and between the pin and lugs 38 and 39.

The operation of this device is as follows: Let it be supposed that the sash is to be raised under which condition the gear in Fig. 4 will be rotated in a left hand direction as indicated by the arrow. By turning the handle the actuator 35 is first turned. This movement causes the lug 39 to press against the end 42 of the spring which tends to uncoil and loosen the spring on the member 33 and release the friction thereof and thereafter the lug engages the pin 40 and drives the gear. Likewise, movement in the opposite direction causes the lug 38 to engage the end 43 of the spring to release it 50 and thereafter turns the gear through the medium of the pin 20 and thus the sash may be raised or lowered. When the sash has been raised or lowered to the desired position the handle is released and as movement 55 of the sash downward tends to turn the gear it will be noted from Fig. 3 that this would cause the pin 40 to engage the end 42 of the spring tending to tighten the same on the member 33 and prevent rotation of the gear. 60 Thus, the sash is locked by the friction of

the spring which is caused to tighten on the boss 33. Therefore, the sash may be readily raised or lowered through the medium of the handle as described and when the handle is released the parts assume practically the 70 position shown in Fig. 4. It requires but little movement of the lug 38 or 39 before it engages the respective ends of the springs and but little further movement is necessary for the pin 40 to engage the said spring ends 75 and thus the slight "lost motion" is quite immaterial in the positioning of the sash.

From the foregoing it is evident that the structure is simple and efficient in operation, that extreme rapidity is secured in the movement of the sash which is counterbalanced, 80 and is automatically locked in position on release of the operating handle.

Having thus fully described our invention, what we claim is—

1. In sash operating mechanism, the combination with a frame and a sash vertically slidable therein, of sash operating mechanism comprising a lazy tongs consisting of two pairs of arms, the first pair being together pivoted near the bottom of the recess, the opposite ends pivotally connected with the ends of the other arms, said other arms being pivoted intermediate their ends and having members at their ends for slidable 95 connection with the bottom of the sash, a cross bar between the vertical members of the frame, a gear train thereon, a handle for operation of one of the gears, a rack engaging another of the gears, a case in which the 100 rack is slidable vertically, a pair of links pivoted to the lower end of the rack at one end and the opposite ends thereof being respectively connected intermediate the ends of the first pair of arms of the lazy tongs, a 10 block to which the second pair of arms are pivotally supported, and a plate having a vertical slot in which the block is slidable.

2. In sash operating mechanism in combination with a frame and a sash vertically 11 slidable therein, of operating mechanism comprising a lazy tongs consisting of two pairs of arms, the first pair being together pivoted near the bottom of the recess and the opposite ends being connected with the 11 ends of a second pair of arms, said second pair being pivoted together intermediate their ends and having members in slidable connection with the sash, a gear train, a rack vertically reciprocable thereby, and links 115 each pivotally connected to the rack at one end and the other ends thereof being pivotally connected intermediate the ends of the first pair of arms.

3. In sash operating mechanism in combination with a frame and sash vertically slidable therein, of sash operating mechanism comprising a lazy tongs fixed in position at one end and connected with a sash at the other, a vertically movable rack, a case 11

in which the rack is guided, a member having a vertical slot positioned below the rack, said rack being formed with a lug to engage the slot, a pair of links pivotally connected with the lower end of the rack and connected respectively with an arm of the lazy tongs whereby movement of the rack up or down raises or lowers the sash, and counter-

balancing springs extending between bars of the lazy tongs tending to extend the same to counterbalance the weight of the sash.

In testimony whereof, we sign this specification.

EDWARD L. ACKERMAN.
ALOIS J. ZWIERZINA.
